METHOD AND APPARATUS FOR PRESSURE TREATMENT

Henri P. L. Laussucq, Reading, Pa., assignor to
Birdsboro Steel Foundry & Machine Company,
Birdsboro, Pa., a corporation of Pennsylvania

Application October 12, 1931, Serial No. 568,486

16 Claims. (Cl. 91—18)

My invention relates to pressing operations.

Most of my disclosure refers to impregnation by pressure against sheet stock which is porous or fibrous, and is to be impregnated, or which is compressible and which is to be resiliently compressed. Where impregnation is intended, a draining background is contemplated, but this is not required where the operation is one of compacting instead. The portion of the invention applied to the sealing under pressure which is greater than the fluid pressure, is independent of the draining background or of the special material operated upon. Where the invention relates to sealing for other purposes, such as hereinafter described, for the purposes of sealing against pipe flanges or surfaces in liquid application to pipe for testing its resistance to pressure, the material of the work will ordinarily not be sheet stock and need have no relation to the fibrous or porous or compactible character of the stock or of any part of it.

In order that the description may be clear and more easily understood, I have applied the invention particularly to operation upon leather, either for filtering purposes through the leather to impregnate the leather or for pressing purposes upon the leather to compact it. Where reference is made to "leather", it is the intention to have the term refer to materials of analogous character or subject to analogous operations.

A purpose is to impregnate sheet stock such as leather under high pressure adapted not only to pass material into and through leather but to force it into the individual fibers of the leather itself.

A further purpose is to support leather by a screen forming a proper backing of the leather, fully preventing driving the leather through the screen, but at the same time permitting the air, the moisture of the leather and the carrier liquid, by which the impregnating material is suspended, to pass through the leather and the screen so that a complete penetration of impregnating material may be permitted without interference by conditions of the leather itself, with regard to air and moisture.

A further purpose is to take the air and the moisture from the leather as a preliminary step to impregnation, following this step by application of impregnating material under pressure while the leather is in the prepared condition.

A further purpose is to apply to a charge under hydraulic pressure a sealing pressure due to the same hydraulic pressure which is in excess of the hydraulic pressure itself.

A further purpose is to subject a charge to fluid pressure and to seal the charge against escape of fluid by a sealing pressure responsive to varia-

tion in the fluid pressure and greater than the fluid pressure.

A further purpose is to seal a material which is to be impregnated by an operation of the press which is doing the impregnating and to intensify the pressure of the seal upon the material being impregnated by reducing the area of the seal as compared with the area of the chamber upon which pressure is exerted in the press.

A further purpose is to effect a seal against a material being impregnated by differential use of the impregnating pressure.

A further purpose is to pass impregnating fluid through a screen-backed material to be impregnated so as to completely saturate the material with impregnating fluid, and to apply it to the material, and subsequently to shut off the exhaust of fluid from the screen so as to raise the pressure throughout the material to be impregnated as compared with the pressure to which the material would be subjected during filtering.

A further purpose is to combine a preliminary filtering operation with a subsequent higher pressure enveloping operation for the purpose of getting the advantage of both in the same material to be impregnated.

A further purpose is to provide a press having a seal which is applied by differential liquid pressure and in which the liquid differential forming the seal is used also for effecting pressure upon the leather, with or without an intervening protective covering to prevent or to permit impregnation of the material being compressed, and, where impregnation is to be permitted, with or without a backing, which will permit filtration through the leather.

A further purpose is to utilize a fluid-applied seal to a charge being pressed, which is the material operated upon during a filtering operation as distinguished from a molding operation.

A further purpose is to connect a pressure chamber within which liquid is contained with a pressure gage to indicate the pressure within the chamber, whether the pressure be absolute for pressing purposes or be variant as in filtering or in impregnating operations.

A further purpose is to connect a pressure chamber containing liquid for impregnating purposes, or which is to be filtered, with a pressure gage, interposing a piston or diaphragm between the liquid whose pressure is to be measured and the gage to prevent clogging of the gage by the liquid, preferably using a liquid intermission material within the gage and replacing intermission material by admitting.

Further purposes will appear in the specification and in the claims.

My invention relates not only to the processes

involved but to apparatus by which these processes may be carried out.

I have preferred to illustrate one main form of the invention only with slight variations, selecting a form which is practical, effective and well suited to commercial operations but which has been selected primarily by reason of its excellence in illustration of the invention.

Figure 1 is a side elevation of a press embodying 10 my invention.

Figure 2 is a right end elevation of the press of Figure 1.

Figure 3 is a section in the plane 3—3 of Figure 1.

15 Figure 4 is a section upon the line 4—4 of Figure 3.

Figure 5 is an enlarged fragmentary sectional elevation upon the line 5—5 of Figure 3.

Figure 6 is an enlarged section upon the line 20 6—6 of Figure 1.

Figure 7 is an enlarged section in the plane 7—7 of Figure 2, in which portions of the outside screen and of the perforated plate have been broken away.

25 Figure 8 is an enlarged fragmentary section in the plane 8—8 of Figure 4.

Figure 9 is a section upon the line 9—9 of Figure 8.

Figure 10 is a fragmentary central vertical 30 section, corresponding generally to Figure 4 and showing a different form of my invention.

Figure 11 is an end elevation, half section, of Figure 10.

Figure 12 is a side elevation of a still different 35 form of my invention.

Figure 13 is an end elevation, half section, of Figure 12.

In Figure 14, a modified form of my invention, 40 is shown in side elevation. In this figure features of the form of Figures 10 and 11 and also of the form of Figures 12 and 13 are included.

Figure 15 is an end elevation, half section, of Figure 14.

Figures 16, 16a and 17 are fragmentary central 45 vertical sections of molds employed in treating sheet material.

Figure 18 is a longitudinal section showing application of my invention to treating a pipe.

In the drawings like numerals refer to like 50 parts.

The mechanism shown is intended to be illustrative merely of one form of mechanism by which the methods can be carried out, it being recognized that the mechanism can be greatly 55 varied both as to the main form and as to the slight modifications illustrated. This mechanism is therefore described for the purpose only of explanation of the invention and not with any thought of restricting the invention by it.

60 Taking up first the description of Figures 1 to 9:

The main features of the press are old, as well known, and comprise any suitable base or bed 20 and top platen 21 connected by tension bolts 22 which guide a cross head 23, which is moved in the 65 pressure direction by a plunger 24 within a main cylinder 25 and which is moved in the opposite direction by pull-back plungers 26 within pull-back cylinders 27.

It will be obvious that the press can be operated either upwardly or downwardly. The use 70 of a downwardly moved press head, in the present instance, has been dictated purely by economy. The press would operate equally as well in the opposite direction so far as convenience of operation is concerned, as the lower head could have

the same character as the lower head shown, whether it be a relatively fixed or relatively movable head.

The cross head is shown as connected by bolts 28 with an upper, in this case a movable die 29, 5 which carries a screen 30. This will be described in more detail later.

The main cylinder 25 receives its hydraulic pressure through a pipe 31 and the pull-back cylinders receive their hydraulic pressure through 10 pipes 32.

The upper die 29 is provided with facing pads 33 (Figure 6) for the attachment of the lugs 34 (Figures 1 and 2) to receive bolts 28 (Figures 1 and 2), a matter of mere convenience in manufacture. The lower face of the upper die is grooved or channeled at 35 (Figure 7) longitudinally, and at intervals also transversely in communication with the longitudinal groove, so as to form paths of flow for fluid material to be 20 drained through channels 36 and 37 (Figures 6 and 7). The channel 37 (Figures 6 and 7) is adapted to receive a pipe 38 connecting with a stop valve 39 operated by a handle 40, and, when the valve 39 is open, connecting through a pipe 25 41 (Figure 2) and a flexible hose 42 (Figure 2) with an exhaust 43 preferably through a vacuum pump 44 (Figure 2).

The grooves or channels communicate with the face of the effective die through apertures 45 30 (Figure 6) in a perforated plate 46 which is intended to mechanically support the work while permitting flow of fluid drained through the apertures and grooves. The perforated plate 46 is preferably not laid directly upon the grooved face 35 of the body of the die for the reason that it is desirable to have an effective seal between them. For this purpose I have shown a sheet of paper 47 which performs this function quite satisfactorily.

The actual contact with the material to be operated upon is preferably made through a screen 48, which may conveniently have a finer mesh than the perforated plate 46, so that for this reason the markings upon the material pressed will be finer and of less destructive nature.

45 The screen 48 is attached to the head by a steel strap 49 held in place by bolts 50.

In the lower die 51, I have shown accommodation for operating on a strip of material 52 much longer than it is wide and for this reason, have divided the plunger operation into two parts so that the liquid is forced against the work strip or charge 52 at two points instead of at a single section near the centre. For a strip of material of different shape it would be desirable to use a single plunger or a greater number of plungers according to the distribution of fluid to the face of the die which is desired.

60 The lower die is best seen in Figures 3, 4 and 5 and its sealing face in Figures 8 and 9. As shown, it comprises a base 53 upon which plungers 54 and 55 are secured by bolts 56. The cylinders corresponding to the plungers are found at 57 and 58 and are formed within a pressure head 59. The connection 60 between the cylinders is needed not only to separate the cylinders but to reinforce the head and prevent injury to the cylinders from the internal pressures applied.

The pressure head is intended to slide down 70 and up upon the pistons and is guided in this movement by the pistons themselves.

The pressure head is spring pressed upward by springs 61 to an extent intended to more than support the weight of the pressure head, so that 75

there will be an initial upward pressure upon the work along the line of the sealing surface 62 seen in Figures 3, 4, 5, 8 and 9.

The upward movement of the pressure head is limited by bolts 63. Leakage past the pistons is prevented by flexible discs 64 held in place by plates 65 fastened in position by screws 66.

By making the pressure head and plunger die the lower die, a liquid which is to be used in it can be poured in through the openings 67 and 68, and the interior space can be cleaned in the depressed position of the pressure head through openings 69 normally closed by plugs 70.

The device as so far described is capable of use in several different ways.

The fluid pressure is developed within the cylinder by downward pressure of the pressure head moving the cylinders upon the plungers or pistons as distinguished from moving the plungers or pistons within the cylinders.

With the construction as shown, the fluid pressure thus secured can be used directly to force liquid against the work (for example to pass it through for impregnating purposes or to force it into a pipe or other object to be tested) while holding the seal against the sheet or against the surface of the pipe or other object which is being tested, or by covering with a protective material as in Figure 16, to force the protecting sheet against material (work) to be compressed so as to apply an effectively fluid face pressure against the material to be compressed, making it possible to compress a variant contour of work to the same extent throughout the entire surface pressed.

To recur to one of the announced purposes of the method and device, the impregnation of such a material as leather with a substance carried within the impregnating liquid, the leather is placed upon the sealing face and the upper die is depressed to bring into contact with the leather the screen or other foraminated surface of the upper die. Enough pressure is applied to compress the springs 61 slightly so as to insure sealing engagement to the surface 62 with the surface of the sheet to be impregnated.

The operation can be performed of course without any special preparation of the leather or other sheet, but I find it to be more effective when the space above the liquid in the lower die and within the screen and discharge passages of the upper die is evacuated by vacuum means prior to the impregnating operation. This removes the air and moisture which might otherwise retard motion and action of the impregnating liquid.

I find further that the continuance of the vacuum application assists in clearing the passages so as to allow freer and more effective flow of the impregnating liquid.

In my use of the term impregnation, I mean to include any operation which is benefited by the high pressures available, giving a better effect than the mere flowing of a liquid through the most obvious passages within the sheet to be treated, to impregnate or coat fibers which would not otherwise be impregnated or coated or to apply the liquid to a greater depth or to a more effective contact with the surface of the fibers than would otherwise take place.

Since the combined area of the ends 71 of the cylinders 57 and 58 is much larger than the area 72 within the outer limits of the sealing surface 62, the fluid pressure developed within the cylinder will be effective to produce a pressure

upon the sealing surface considerably in excess of the pressure developed within the cylinders and therefore in excess of the pressure which is exerted upon the work which is being impregnated or pressed.

The lower die 51 is free to move downward under the action of the upper die, as previously explained, and, as it moves downward about the plungers 54 and 55, causes compression of the liquid within the cylinders 57 and 58, the openings 67 and 68 and the depressed space above them. Everywhere throughout the liquid content the pressure is the same, but the force exerted upon various surfaces is a function of their areas.

When equilibrium is established the force upwardly upon the lower die 51 is equal to the cross sectional areas of the cylinders 57 and 58 less the cross sectional areas of the openings 67 and 68, all multiplied by the pressure of the liquid, neglecting the effect of the springs 61, whose force is trivial in comparison to the large hydraulic forces present. The force downwardly upon the lower die 51 is equal to the force of the upper die on the sealing surface 62, plus the downward force of the liquid on the lower die. The downward force of the liquid on the lower die equals the area inside of the sealing surface 62 less the cross sectional areas of the openings 67 and 68, all multiplied by the pressure.

The force on the sealing surface 62 is therefore equal to the upward force on the lower die 51 minus the downward force on the lower die 51 due to the liquid. Stated in another way, the sealing force is equal to the cross sectional area of the cylinders 57 and 58 minus the area inside of the sealing surface 62, all multiplied by the pressure. The cross sectional areas of the openings 67 and 68 may be neglected, as they cancel out. The sealing pressure is equal to the sealing force divided by the area of the sealing surface 62, and, as just stated, the sealing force is equal to the difference between the total cross sectional areas of the cylinders 57 and 58 and the area inside of the sealing surface 62, all multiplied by the pressure. Therefore, as long as the total cross sectional areas of the cylinders 57 and 58 are greater than the areas inside of the sealing surface 62 plus the area of the sealing surface 62, the sealing pressure will be greater than the fluid pressure. In other words, the total cross sectional areas of the cylinders should be larger than the area 72 within the outer limits of the sealing surface 62.

Not only is this generally true for any pressure, but the excess of pressure of the sealing face against the work over the fluid pressure by which it is effected continues throughout the range of pressures, bearing a relation to the pressure within the cylinders at all times but increasing with increase of fluid pressure and reducing with reduction of fluid pressure.

The sealing face 62 preferably covers a considerable total area broken up into spaced ribs 73 producing a general sawtooth effect in cross section as seen in Figure 9. This is for the purpose of producing an artificially extended sealing surface having grooves and ribs of the sealing face of the lower die which engage the work.

Where a pressure is applied directly by the movable head some fairly accurate idea of the effect of pressure on the surface can be obtained from the pressure gage of the intensifier or accumulator pressure applied to the piston or plunger, but when the pressure is reactionary pressure as

in the present case, produced in the fluid content of a two part lower die by reaction against the pressure from the upper die, determination of the pressure by the accumulator or intensifier pressure is not so satisfactory.

For this reason I have provided means for more directly measuring the pressure within a cylinder or the cylinders of the lower die and at the same time protecting against leakage of the fluid within the lower die. This protection is desirable because the liquid within the cylinders of the lower die may be surcharged with impregnating material or for different purposes may otherwise be of such constitution that it should be conserved or that it would undesirably effect the pressure gage mechanism used.

In order to measure the pressure of a cylinder or the cylinders in the lower die, I provide a fluid passage 74 in communication with the cylinder or cylinders, with which passage a pressure gage 75 is connected through an intermediate chamber 76 within a fitting 77. The chamber 76 accommodates a piston 78, which is packed at 79 and 80 and which is moved by fluid pressure within the passage 74. The piston operates upon a content 81 which may be grease or other suitable material, and which is itself effective to operate the pressure gage 75.

The chamber 76 is connected with the pressure gage through a passage 82, which passage is extended at 83 into communication with a valve 84 and a fitting 85, such as of Alemite type, by which, when the valve is open, the filling within chamber 76 may be inserted initially or augmented subsequently to keep the device in operative condition.

Because it is necessary to fill the cavities in the chamber and pressure gage, the filling must be put in under considerable pressure such as is obtainable by the use of a syringe of the Alemite type.

The filling operation is performed at a time when there is no fluid pressure within the cylinders 57 and 58. After the pressure gage begins to indicate, the valve 84 is closed in order to protect the fitting 85 from the pressure to which it would be subjected when the fluid pressure is raised in the cylinders 57 and 58.

In Figure 10 the structure is of the same general character and the operation may be the same as in Figure 4, with the exception that the bed or lower part of the lower die is divided to provide two parts 86 and 87, which form a curved joint between them, so that the part 86 can turn 55 in the part 87 to accommodate difference in thicknesses of the material operated upon or variations in position of a piece to which the pressure is to be applied, as would be the case in variations of position of the flange or of a surface of pipe which is to be tested by fluid pressure. Where the sealing surfaces 62 surround an elongated space, such as is shown in Figures 10 and 11, the purpose above would be subserved in large measure by a cylindrical surface only, 65 between the parts 86 and 87, permitting movement in planes parallel to the planes of the paper, but I have preferred to form a spherical joint 88 between the parts, so that adjustment may take place in all directions until the pressures are 70 equal about the periphery of the sealing surface.

As long as the lower die is resting upon the bed of the machine, the weight of the parts will hold them together and no separate means is required to maintain the parts in operative relation. In Figures 14 and 15 where the parts are

lifted bodily, provision is made to keep the spherical base socket in contact with the ball which it sockets.

The ball and socket support for the lower die is supplemental and need in no way affect the 5 operation of the rest of the parts of the device. It provides an additional capacity for the additional function of accommodation of the seal to different slopes of surface of the work, automatically taking care of any slope which may 10 be present.

Preferably the center of curvature of the ball support lies in the work so that there may be no lateral movement of the sealing surfaces with an 15 accommodation of the seal to the slope but only tilting of the surface.

This is of value in avoiding scraping of the work by the sealing surfaces whether the operation be one of impregnation or one of compression.

Where a cylindrical or spherical joint is provided between parts of the base to accommodate for variations in pressure or position of the work with which contact is to be made, it is quite desirable to lubricate this joint and I have taken care of it by a lubrication space 89 (Figures 10 and 11) and lubricating passages 90 and 91 connecting with it, the lubricant being introduced by any suitable means.

In Figures 12, 13, 14 and 15 the pressure head 30 of the lower die is supported by hydraulic plungers 92 fitting the hydraulic cylinders 93 which may be additional to the springs 61 or may be used wholly instead of these springs if desired.

In Figures 12 and 13 this feature is applied to a 35 form of the invention corresponding generally with that shown in Figures 1 to 9, while in Figures 14 and 15 it is applied to the variation shown in Figures 10 and 11.

The difference between Figures 12 and 13 on the one hand, and Figures 14 and 15 on the other hand, due to the difference in structure between Figure 4 for example, and Figures 10 and 11, lies in the fact that in Figures 14 and 15 provision is made for lifting the socket of the ball joint 45 formed between the parts of the base of the lower die, and not only allowing the two parts of the ball to drop, but providing for additional movement of the pressure head with respect to the base.

In all of Figures 12, 13, 14 and 15, the support of the pressure head by the hydraulic plungers not only affords a substitute for the springs in whole or in part, but makes it possible by relieving the fluid pressure after operation begins 55 to avoid necessity for compressing against this resilient pressure. The springs or the push-back pistons 92, may still have useful functions in additionally insuring against loss of seal during the pressing operation.

In all of Figures 12, 13, 14 and 15, where the entire base of the lower die is lifted along with the pressure head, the construction makes it possible to effect a reliable seal, at any pressure desired, between the sealing surface 62 and the work 65 before any fluid pressure is exerted upon the pressure head and to maintain or assist in the seal by the hydraulic pressure provided throughout the entire pressing operation if desired. In this event, the entire lower die is lifted into pressure-sealing engagement with the work after the upper die comes down, or to a positive stop where the upper die meets after the upper die comes down and the entire lower die is subsequently pushed down by the upper die until the 70 75

base comes in contact with the bed of the press, after which the operation is the same as with the forms of Figures 1 to 9 except in so far as the use of the hydraulic pressure continuously 5 upon the pressure head causes an additional safe-guard against breakage of the seal.

Positive stops for limiting the upward movement of the pressure head are shown in the bolts 94.

10 In Figures 14 and 15, the socket 87 is connected with the pressure head by links 95 secured through pins 96 at the bottom and 97 at the top. The pins 97 normally fit into the upper ends of slots 98 in such position as to hold ball and socket members together, while the base parts 86 and 87 are being lifted from the pressure head by means of the hydraulic push-up plungers 92. When the effective seal has been formed above, the position at which development of pressure within the 20 pressure head begins (above, because the push-up plungers have lifted the entire lower die member), further downward movement of the upper die member pushes the entire lower die member downwardly without causing relative movement 25 between the pressure head and the base until the space 99 is closed and the base seats upon the press bed at 100.

In Figure 16, I have shown an upper die 100 which does not have fluid drainage provision, 30 but instead is provided with a face 101 which is suited to give a formation to leather or other sheet material, fibrous or otherwise, which is to be compressed, and I have effected the compression by mechanism of the same character otherwise as shown in Figures 1 to 9, except that the fluid pressure of the lower die does not come in direct contact with the sheet (work) 102, but instead makes the seal at 103 with an intervening flexible protective cover 104 conveniently secured 40 in its position by any suitable means as at 105.

The seal is the effective means for holding this protective cover 104 and preventing leakage above it, and the fluid pressure within the space 106 provided by the seal presses against the surface 45 of the cover away from the work, giving uniform pressure upon the work, whether it be of regular or irregular face contour, conforming to irregularities in the surface and effecting resilient pressure compression notwithstanding the irregularities.

50 It is thus possible to press work of irregular contour on both sides, producing as in Figure 16a, at 107, for example, outer and inner generally parallel surfaces of any form determined by the shape of the face of the upper die.

It will be recognized that by shaping the upper foraminous die in Figures 1 to 9 irregularly, the pressure required to force liquid through the work may be made to conform the work to the 60 irregular shape of the under face of the upper die before filtration through the work begins, or during this filtration or permeation, and the permeating liquid is useful in softening a material (work) which otherwise would not lend itself to distortion.

65 In Figure 16a the upper die 29' may have any odd shape of undersurface and the material 107 operated upon may be metal, for example stock for trays, without the necessity for use of a protective surface, if the character of the surface of the stock itself be such that a liquid seal may be made with it.

To facilitate the liquid seal on metals, a sealing ring 108 is shown which may be of leather or 75 rubber.

This form without a protective surface is effective for any material, where the permeation of liquid through the material at the seal is not too rapid to permit practical sealing at the pressures used, and where the material operated upon is not so porous as to allow the pressure liquid to pass through it before it shall have been conformed to the shape of the upper die.

In Figure 17, I have shown a retaining ring 109 secured to one of the heads, preferably to the upper head over the screen, and corresponding to the outline of the work upon which we are operating. It is effective during impregnating operations or pressing operations to protect the edges of the material (work) against spreading 15 of the material.

In Figure 18, I have applied my invention to the development and control of pressures within articles (work) to be tested, the particular article shown being a water pipe 110. The die corresponding with the upper die is shown at 111 and forms a seal with or without intermediate gasketing at 112 with the face flange 113 at this end of the pipe.

The plunger or ram 114 in cylinder 115 may be subject to several pressures if it be desirable to work to the best fluid pressure economy. A low pressure supply through inlet 116 is shown to form the initial seal by pressing the opposite end of the pipe against a gasket or other sealing surface 117 resting upon or integral with the pressure head 118 which is apertured at 119 for the passage of fluid within cylinder 120.

The plunger 121 is supported upon the base 122 and fluid pressure is inserted within cylinder 120 through a pipe 123 valved at 124.

The pipe 123 affords a means of filling not only cylinder 120 and aperture 119 with liquid but for filling up the work to be tested; in this case the interior of the pipe with fluid. After this has been accomplished high pressure is introduced to the cylinder 115 through a source of high pressure 125 to cause the plunger or ram 114 to move the cross head 111, moving the pipe and pressure head to make effective pressure thus produced by constricting the space in the cylinder 120. A gage 126 indicates the pressure secured.

The pressure head may be outwardly pressed by the springs shown or by other suitable means and the cross head may be retracted and plunger 114 drawn back by any suitable push-back or pull-back means, in the present instance shown as a counterweight cord 127 passing over sheave 128 to a counterweight 129.

In operation of the form shown in Figures 1 to 9, I place impregnating fluid in the depression in the lower die and then insert upon the lower die and in engagement with the sealing edges of the lower die, a sheet to be impregnated.

The spaces within the passages of the usual die and interstices of the sheet to be treated and above the liquid in the lower die are preferably exhausted of air and moisture by vacuum or other means after the seal has been effected. This is for the purpose of having as little interference with complete engagement of the impregnating liquid with the fibres of the sheet as possible.

The upper die is then depressed by applying pressure to the main cylinder, so that the upper die engages the upper surface of the sheet above the sealing edges.

Pressure of the upper die transmitted through the sheet causes downward movement of the pressure head of the lower die against the action 75

of the springs. As the pressure head of the lower die moves downwardly, the impregnating liquid is finally compressed by the plungers in the lower die, thus forcing the sheet firmly against the 5 whole surface of the upper die.

As further pressure is applied to the main ram, the pressure of the impregnating fluid held in the lower die increases, until finally it is sufficient to force the impregnating fluid into the 10 sheet and finally through the sheet and through the screen upon the lower surface of the upper die. At this point the impregnating fluid is normally removed by suction.

In passing through the sheet, the impregnating fluid will not only penetrate all openings in the sheet, but will deposit, in the pores of the sheet, any suspended matter carried by the impregnating fluid. Thus as the impregnating fluid is forced through the sheet, it will leave in the pores 20 of the sheet a progressively-increasing quantity of suspended matter, due to the filtering action of the leather itself.

My lower die is so constructed that the pressure of the sealing surfaces of the lower die against 25 the leather or other material being pressed is in excess of the pressure against the leather. This is due to the fact that the area of the lower die pistons is greater than the area of leather exposed for treatment.

30 Furthermore, as the pressure in the impregnating fluid builds up, the sealing pressure likewise increases in proportion, always bearing a suitable predetermined relation to the pressure upon the object being pressed. There is thus no 35 danger that the sealing pressure will at any time be too low.

The same method of applying increased sealing pressure may equally well be used for other purposes, as for example, to engage the ends of 40 piping to hold it in position for bursting tests.

What I have described as impregnating material because of its highly efficient use in impregnating leather, for example, might perhaps more aptly be called a treating material because 45 of its broader application to all sorts of uses; and the material used may act upon the work by deposition of suspended matter or by impregnation with liquid having fully dissolved matter in it incapable of being filtered out by the operation 50 or may be made capable of chemical reaction upon the interior fibers or surfaces of the sheet.

The treatment may be hot or cold, may be 55 successful with different materials for mordant and dye purposes or separate dye purposes or may otherwise be variant for purposes of securing chemical, mechanical or combined results. With a single liquid or where a succession of liquids is used the length of time of treatment with the liquids may become important as also the depth 60 of penetration of the individual liquids into the individual fibers of the sheet, for control of which operations my method of stopping the operation by closing the valve and applying the pressure up to the maximum pressure available is highly 65 effective. This gives control not only of the pressure but of the time of application.

It will be noted that the push-back plungers in 70 Figures 14 and 15 do not engage directly against the under side of the pressure heads but engage 75 with small blocks shown as of the same diameter as themselves which are free to slide against the under face of the pressure head and which have spherical bearing with the plungers whereby the plungers and these blocks together accommodate themselves to tilting of the pressure head.

As I have shown in Figures 16, 16a and 17, the same succession of steps minus the discharge of fluid on the other side permitting filtration can be utilized with or without a protecting surface for application of pressure to compress or to form the work, using the face opposite the effective fluid pressure either as an abutment merely or to give a surface to the material pressed or to control the design or shape of one or both sides of the material pressed.

As shown in Figure 18 the same provision for effective pressure may be utilized to apply pressure within a closed receptacle for test purposes.

The variant showings of impregnation, distortion, die formation of surface, protection of surface, or pressure available for special purposes are all effective along with my sealing means though in Figure 18 there is not the same necessity for the use of this seal as in the other figures. These various forms are given for the purpose of showing the breadth of application of the various features of my invention and to lay a foundation for divisional applications to cover the processes and apparatus disclosed if it becomes desirable to divide out this subject matter from the present case.

Without attempting to give any considerable number of liquids which may be used, but for the purpose of showing practical application I would suggest that neat's-foot oil, gilsonite oil, carbon tetrachloride, rubber solution, nitro-cellulose solution, grease, colloidal solutions, insecticides and other liquids having solids in solution or suspension may be used to accomplish their now recognized or new benefits and that for pressing purposes oil or water or other suitable content may be used.

It will be evident that my sealing method and mechanism are effective to hold around the edges 40 a sheet or other material which is to be distorted by pressure, preventing wrinkling during the distorting operation.

Sealing by axial pressure with the same area within the seal as within the pressure cylinder, and pressure for impregnating purposes with a 45 seal but without release of the liquid at the back of the sheet to permit flow through are not new to me, and it is not my intention to claim my invention broadly enough to include these.

In view of my invention and disclosure variations and modifications to meet individual whim or particular need will doubtless become evident to others skilled in the art, to obtain part or all of the benefits of my invention without copying the structure shown, and I, therefore, claim all 55 such in so far as they fall within the reasonable spirit and scope of my invention.

Having thus described my invention, what I 60 claim as new and desire to secure by Letters Patent is:

1. The method of impregnating a material with a substance contained in a liquid which consists in supporting the material by a screened surface to prevent the material from being forced through the screen, while permitting air and liquid to pass through the screen, in forcing liquid containing an impregnating substance through the material at high pressure to deposit the substance upon and within the fibres of the material to be impregnated and in utilizing the pressure of the 70 liquid to form a seal against the material to be impregnated effective as a seal in proportion to the pressure of the liquid.

2. The method of applying increased pressure to a surface or body to which the pressure is to 75

be applied which consists in resiliently sealing against the work and in pressing the resilient seal in a direction to restrict the volume of a fluid pressure cylinder in communication therewith and having a larger cross sectional area than that covered by the seal whereby a part of the pressure is applied to the seal.

3. The method of compressing or distorting a material operated upon against a die face which 10 consists in relatively moving the die face and a seal of restricted area to engage the seal with work placed between them and in continuing the relative movement to restrict the volume of a space of greater area than the sealing area to 15 bring pressure of extruded liquid against the material to be operated upon.

4. The method of impregnating materials or producing pressures upon a surface which consists in providing a seal of limited area about 20 the surface and in relatively moving the seal and a body of fluid of larger cross sectional area than the seal to react through the seal and upon the seal to intensify the pressure upon the seal and produce the pressure required within it.

25 5. An hydraulic press die comprising relatively movable parts of which the outer part carries a seal and the inner part plunger means adapted to operate within cylinder means on the inside of the outer part of the die in communication with the 30 space within the seal, the area included within the outside of the seal being less than the cross-sectional area of the cylinder means.

6. An hydraulic press die comprising relatively movable outer and inner die parts having a seal 35 on the outside of the outer part, cylinder means on the inside of the outer part communicating with the interior of the seal and of cross-sectional area larger than the area of the outside of the seal and resilient means for pressing the 40 outer part outwardly with respect to the inner part.

7. An hydraulic press die having a seal upon its outer face and hydraulic means for expressing liquid from the interior of the die into the 45 space within the seal at a unit pressure less than the pressure of the seal against the work in combination with a vacuum filter die and means for closing the outlet to the filter.

8. An hydraulic press die having a seal upon 50 its outer face and hydraulic means for expressing liquid from the interior of the die into the space within the seal at a unit pressure less than the pressure of the seal against the work and a protective face for the work adapted to engage the seal.

9. A die for a press comprising a pressure member carrying a sealing outer face and a cylindered inner face in communication with the space within the seal, plunger means for causing expression 60 of liquid from the cylindered parts with relative movement and resilient means for normally holding the parts separated, the combined cylinder area being in excess of the area included within the outer parts of the seal.

65 10. In an hydraulic press a die having a seal upon its outer face and means effective upon pressure against the die for expressing liquid under pressure into the space within the seal of the die and a gasket seal effective between the work and the interior of the seal.

11. An impregnating press comprising a filter head and a head cooperating therewith having a plunger and an intervening cylinder head sur-

rounding the plunger and having sealing engagement with the work of smaller area than the cross-sectional area of the plunger.

12. A method of impregnating sheet material with an impregnating fluid, comprising confining the fluid in a basin, arranging the sheet to be impregnated across the top of the basin, sealing the line of contact between the sheet and the mouth of the basin to prevent the impregnating fluid from escaping through this line, 10 then exerting pressure upon the fluid in the basin to cause the fluid to move upwardly and penetrate the sheet, and increasing the effectiveness of the seal as the impregnation pressure is increased.

15 13. An article impregnating apparatus comprising a piston member, a cylinder member, said members forming a variable sized basin over the mouth of which the article to be impregnated may be placed, one member being movable relatively to the other, pressure exerting means for causing one of said members to move relatively to the other for forcing an impregnating fluid from the basin into an article arranged across the mouth of the same, and means for effecting 20 a tight seal between the article and the mouth of the basin by the action of the pressure of the impregnating fluid.

25 14. An article impregnating apparatus comprising a piston member, a cylinder member, said members forming a variable sized basin over the mouth of which the article to be impregnated may be placed, one member being movable relatively to the other, pressure exerting means for causing one of said members to move relatively to the other for forcing an impregnating fluid from the basin into an article arranged across the mouth of the same, means for effecting a tight seal between the article and the mouth of the basin, by the action of the pressure of the impregnating fluid, and yielding means for normally holding said members in definitely spaced relation.

30 15. An article impregnating apparatus comprising a piston member, a cylinder member, said members forming a variable sized basin over the mouth of which the article to be impregnated may be placed, one member being movable relatively to the other, pressure exerting means for causing one of said members to move relatively to the other for forcing an impregnating fluid from the basin into an article arranged across the mouth of the same, and means for effecting a tight seal between the article and the mouth of the basin by the action of the pressure of the impregnating fluid, the last mentioned means including a shoulder in the cylinder member co-operating with said piston member.

35 16. An article impregnating apparatus comprising a piston member, a cylinder member having a bore for the piston member, an annular shoulder formed by the cylinder member and arranged at the upper end portion of the bore, said members forming a variable sized basin over the mouth of which an article to be impregnated 50 may be placed, and pressure exerting means for simultaneously causing one of said members to move relatively to the other for forcing an impregnating fluid from the basin into an article placed across the mouth of the basin and for 55 effecting a tight seal between the mouth of the basin and the article.

HENRI P. L. LAUSSUCQ.
